DESIGN FOR A SUN GOGGLE OR THE LIKE

Harry C. Richards, Morristown, N. J., assignor to Fosgood Corporation, Leominster, Mass., a corporation of Massachusetts

Application August 12, 1944, Serial No. 114,872

Term of patent 14 years

(Cl. D57—1)

To all whom it may concern:

Be it known that I, Harry C. Richards, a citizen of the United States, residing at Morristown, in the county of Morris, State of New Jersey, have invented a new, original, and ornamental Design for a Sun Goggle or the like, of which the following is a specification, reference being had to the accompanying drawing, forming part thereof, in which:

Fig. 2 is a top plan view; and
Fig. 3 is a side view thereof.

The temples are shown fragmentarily in Figs. 2 and 3 for convenience of illustration.

I claim:

The ornamental design for a sun goggle or the like, substantially as shown and described.

HARRY C. RICHARDS.
